DOOR STOP

Joseph L. Ventura, Park Ridge, Ill.

Application March 20, 1935, Serial No. 11,949

9 Claims. (Cl. 292—17)

This invention relates to a door stop and more particularly to a combined door cushion and catch, although certain features thereof can be employed with equal advantage for other purposes.

It contemplates more especially the provision of a simple, inexpensive and improved door cushion and stop that can be utilized in conjunction with doors that open both parallel as well as angularly to a wall.

Numerous types of door stops have heretofore been proposed, but these are expensive and require modifications in form in order to afford their use with a door that opens parallel to a wall or angularly thereto to serve as a stop therefor. Then, too, the door stops of known construction do not provide for a cushioning effect when the door is swung open at a terrific speed to the end that the door stop receives an excessive impact without absorbing the shock through the medium of the resilient catch.

One object of the present invention is to simplify the construction and improve the operation of devices of the character mentioned.

Another object is to provide a durable, inexpensive and effective door cushion and catch that is operable in a variety of positions.

Still another object is to provide a resilient door catch that is complementary to a stop so as to be capable of axial or angular engagement or disengagement.

A further object is to provide a door stop having a plurality of obstructions for cooperation with a door catch so as to arrest the opening of a door without shock even though such is displaced at an excessive speed.

A still further object is to provide a resilient door catch as co-operable with a door stop having a series of obstructions to absorb the shock of impact irrespective to the speed of door displacement.

Still a further object is to provide a door stop having means co-operable with a resilient catch member in either an angular or axial direction to absorb the shock of impact and to retain the door in an open position.

Other objects and advantages will appear from the following description of an illustrative embodiment of the present invention.

In the drawings:

Figure 1 is an enlarged fragmentary perspective view of a door stop and catch embodying features of the present invention.

Figure 2 is a sectional view taken substantially along line II—II of Figure 1 when the door is

opened to bring the door stop and catch in connected relation.

Figure 3 is a sectional view taken substantially long line III—III of Figure 2.

Figure 4 is a sectional plan view showing the 5 operation of the door stop and catch shown in the previous embodiments when applied to a door that opens in angular relation to a wall and serves as a stop therefor.

Figure 5 is a perspective view in elevation of 10 the door stop and catch shown in the position of engagement illustrated in Figure 4.

Figure 6 is a sectional plan view showing the 15 method of attaching the catch to the door with the former engaging a stop beyond the first ob- 15 struction.

Figure 7 is a perspective view of a door stop embodying features of the present invention.

The structure selected for illustration comprises an elongated stop member 10 that is cast or otherwise shaped from metal to define an enlarged base 11, in this instance, of rectangular configuration. The base 11 merges with a tapered boss 12 that terminates in an axially extending elongated shank 13 which is also tapered, but to a lesser degree than the boss 12 in order to provide an enlarged base 11 to withstand the strains and impacts that are imparted thereto.

As shown, the shank 13 has an intermediary transverse reinforcing rib 14 that extends around the periphery thereof, but such also serves as an ornamental feature to correspond in design with another transverse peripheral ridge 15 disposed proximate to the free extremity of the shank 13. The transverse peripheral ridge or obstruction 15 confronts a much larger peripheral ridge 16 that is spaced forwardly therefrom to define an annular transverse groove 17 that serves to receive the catch in its extreme displaced position as will appear more fully hereinafter.

Another annular groove 18 is formed forwardly of the peripheral obstruction 16 for initial reception of a catch member which is designed to be displaced over a tapered head 19 formed integrally with the shank 13 with its largest dimension 20 formed adjacent the annular groove 18. As shown, the head 19 is tapered and converges in the direction of its tip 21 which is sufficiently small to initiate registry with a catch that will be described hereinafter. It is to be noted that the door stop head 19 has rounded edges 22 inclined to conform with the tapered configuration thereof and to permit displacement of the catch thereover in most any direction or position. In order to sustain the door stop 10 or to enable its 55

attachment to a wall, base board, or floor for positioning in the path of a door fastening expedient such as a wood screw 23 axially extending from the base 11 in a direction normal to the 5 surface thereof. The fastening expedient 23 is preferably though not essentially formed integral with the door stop 10, and enables the attachment thereof to any suitable support such as the base board 24 that is disposed along the 10 bottom of a wall 25 to serve as a trimming therefor.

In order that a door 26 that is mounted for swinging movement relative to a wall 25, may be brought to a stop and held in an open position, 15 the door catch is secured thereto for cooperation with the stop 10. To this end the door catch comprises, in this instance, a substantially U-shaped member 27 which is stamped or otherwise shaped from sheet material to define upstanding and confronting arms 28 and 29 preferably though not essentially formed integral with an intermediate portion or base member 30. As shown, the arms 28 and 29 terminate in inwardly directed and convexly curved extensions 31 which 20 confront each other to define inwardly directed projections that conform in curvature with and serve as a complement of the annular grooves 17 and 18 depending upon the degree of displacement of the door catch 27 over the head 19 of the 25 elongated stop 10.

It is to be noted that the arms 28 and 29 of the catch 27, are resiliently disposed relative to each other so as to be capable of flexing and conform with the configuration of the head 19 as well as 35 grooves 17 and 18 of the stop 10 for engagement and disengagement therewith. To this end, the door catch 27 is provided with an aperture 32 in the intermediate or base portion 30 so as to receive a fastener such as a wood screw 33 there-through for attachment of the catch 27 to the door 26 in a position so as to confront the door stop 10 when displaced to its extreme open position. This can be accomplished and the exact 40 position found by first attaching the door stop 45 10 to the base board 24 of the adjacent door wall within the limit of its confronting extent in an open position. Thereupon, the door catch 27 is fitted over the head 19 of the stop 10 so that the arcuate extensions 31 thereof will engage the 50 groove 17 so as to hold the screw 33 in its projected position because of its contact with the stop head 19 (Figure 6).

The door 26 can be opened so that the extremity of the screw 23 will leave an impression of 55 its proper positioning and attachment. The catch 27 is then removed from the door stop 10, and its screw 33 fastened in the usual manner so as to maintain the door catch 27 in its proper attached position. The door 26 may then be 60 opened and retained in its extreme opened position by displacement in the direction of the door stop so that the door catch 27 will be displaced thereover for engaging either the groove 18 or 65 17 depending upon the speed of displacement and the degree of impact. If the degree of displacement is so excessive as to preclude the first peripheral obstruction 16 to stop the catch 27 so that its arcuate extensions 31 will absorb the shock owing to their resilient character, further 70 displacement of the door catch 27 thereover will take place and the obstruction 15 will thereupon serve as a stop to lodge the arcuate door catch extensions 31 within the groove 17.

In consequence thereof, the door will be 75 stopped and cushioned without any damage or

appreciable noise irrespective of the speed of displacement and the degree of impact. The door will not, thereafter, swing freely to its closed position, but will be retained open until purposely displaced by an attendant who will have to apply 5 sufficient force to effect the displacement of the catch 27 from the stop 10.

There are numerous occasions wherein a door 26' is mounted to swing open relative to a wall 25' disposed at an angle thereto when the door 10 26' is in its extreme open position (Figure 4). In order that the door stop 10 and catch 27 may be utilized for such installations, provision is made for the engagement of the catch 27 at an angle with the door stop 10. In the present embodiment, this is accomplished by providing arcuate notches 34 in the obstructing peripheral ridge 16 intermediate the corners thereof. The notches 34 substantially conform in curvature with and serve as a complement of the arcuate 20 catch extensions 31 which are lodged therein at an angle for retention (Figure 5).

With this arrangement, the extensions 31 of the door catch 27 are first displaced over the head 19 of the stop 10 at an angle for lodgment in the 25 arcuate notches 34 rather than the transverse annular grooves 18 for cushioning and effecting the stop of the door 26'. The retention thereof is also effected, and this arrangement of parts and features provides an effective and combined 30 cushioning and stopping expedient for doors that open both parallel as well as angularly to a wall 25 in its open position. A very inexpensive, durable and effective door cushion and stop member has been provided, and is possessed of combined 35 advantages not found in any of the known devices utilized for the same purpose.

Various changes may be made in the embodiment of the invention herein specifically described without departing from or sacrificing any 40 of the advantages of the invention as defined in the appended claims.

I claim:

1. In a device of the character described, the combination with an elongated bolt member 45 comprising a tapered head, a fastener screw formed integral with the said stop member for axial extension from the end opposite its tapered head, said bolt being adapted to coact with a spring clip member, an abutment ridge on said 50 elongated bolt member in spaced relation with its head for frictionally retaining the spring clip therebetween, said abutment ridge having notches to enable angular frictional engagement and retention of said spring clip relative to said 55 stop member head.

2. In a device of the character described, the combination with an elongated bolt member, comprising a tapered head, a fastener screw formed integral with the said bolt member for axial extension from the end opposite its tapered head, said bolt being adapted to coact with a spring clip member, an abutment ridge on said 60 elongated bolt member in spaced relation with its head for frictionally retaining said resilient 65 clip therebetween, said abutment ridge having transverse notches provided therein to enable the angular frictional engagement and retention of said spring clip relative to said stop member head.

3. In a device of the character described, the combination with an elongated bolt member comprising a tapered head, a fastener screw formed integral with the said bolt member for axial extension from the end opposite its tapered 70 head.

- head, said bolt being adapted to coact with a spring clip member, a peripheral abutment ridge encircling said elongated bolt member in spaced relation with its head for frictionally retaining 5 said resilient clip therebetween, said abutment ridge having slots interrupting the continuity thereof for enabling angular frictional engagement and retention of said spring clip, and another abutment ridge on said elongated bolt member spaced from said first named abutment ridge to serve as a secondary stop for said clip when engaging said stop member head with excessive impact for said first named abutment ridge to halt the displacement of said spring clip.
- 10 4. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, said abutment ridge being in the path of said bolt for frictional engagement and disengagement with said bolt member 15 head, and another peripheral abutment ridge on said elongated bolt member spaced from said first named abutment ridge to serve as a secondary stop for said clip when engaging said bolt member head with excessive impact for said first 20 named abutment ridge to halt the displacement of said spring clip.
- 15 5. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, said abutment ridge having notches to enable the angular frictional engagement and retention of said clip relative to said bolt member head, and another abutment ridge on said elongated bolt member spaced from said first named abutment ridge to serve as a secondary stop for said clip when engaging said stop member head with excessive impact for said first named abutment ridge to halt the displacement of said spring clip.
- 20 6. In a device of the character described, the combination with an elongated bolt member comprising a tapered head said bolt being adapted to coact with a spring clip member, a peripheral abutment ridge encircling said elongated bolt member in spaced relation with its head for frictionally retaining the spring clip therebetween, and another abutment ridge on said elongated bolt member spaced from said first named abutment ridge to serve as a secondary stop for said clip when engaging said bolt member head with excessive impact for said first named abutment ridge to halt the displacement of said spring clip.
- 25 7. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, and said abutment ridge having notches interrupting the continuity thereof to enable angular frictional engagement and retention of said spring clip relative to said 30 bolt member head.
- 30 8. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, and said abutment ridge having notches interrupting the continuity thereof to enable angular frictional engagement and retention of said spring clip relative to said 35 bolt member head.
- 35 9. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, said abutment ridge having notches intermediate the extremities thereof to enable the angular frictional engagement and retention of said spring clip relative to said bolt member head, and another abutment ridge on 40 said elongated bolt member spaced from said first named abutment ridge to serve as a secondary stop for said spring clip when engaging said bolt member head with excessive impact for said first named abutment ridge to halt the displacement of said spring clip.
- 45 10. In a device of the character described, the combination with an elongated bolt member comprising a tapered head, a fastener screw formed integral with the said bolt member for axial extension from the end opposite its tapered head, said bolt being adapted to coact with a spring clip member, a peripheral abutment ridge on said elongated bolt member in spaced relation with its head for frictionally retaining said resilient clip therebetween, said abutment ridge having notches interrupting the continuity thereof to enable angular frictional engagement and retention of said spring clip relative to said bolt member head, and another abutment ridge on 45 said elongated bolt member spaced from said first named abutment ridge to serve as a secondary stop for said spring clip when engaging said bolt member head with excessive impact for said first named abutment ridge to halt the displacement of said spring clip.
- 50 11. In a device of the character described, the combination with an elongated bolt member comprising a tapered head, said head being of rectangular configuration, a fastener screw formed integral with the said bolt member for axial extension from the end opposite its tapered head, said bolt being adapted to coact with a spring clip member, a peripheral rectangular abutment ridge on said elongated bolt member in spaced relation with its head for frictionally retaining said resilient clip therebetween, said clip having
